UNITED STATES PATENT OFFICE

OTWELL G. PETTYJOHN, OF PHILADELPHIA, PENNSYLVANIA

BURGLAR ALARM

Application filed July 21, 1931. Serial No. 552,176.

My invention relates to new and useful improvements in a burglar alarm and especially to that type of such alarms as which serve to lock the upper and lower sash of a window against being opened from the outside and has for its object to provide a bell so mounted that it may be swung over the upper rail of the lower sash of a window or out of alignment therewith for putting into and out of operative positions.

A further object of my invention is to provide for an automatic spring action which will always tend to put the alarm in operative position upon the closing of the lower sash.

A still further object of my invention is to so construct the device that it will be cheap to manufacture, simple to apply and easy to operate.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is an elevation of a portion of a window frame and the sashes fitted thereto showing my improved burglar alarm applied to the frame and in operative position relative to the sashes.

Fig. 2 is a view at right angles to Fig. 1.

Fig. 3 is a section at the line 3—3 of Fig. 2, looking downward and showing the alarm set in operative position in full lines and just prior to being set in such position, in dotted lines.

In carrying out my invention as herein embodied, 10 represents the alarm bell which is of the type commonly known as a bicycle bell, the ringing mechanism thereof being enclosed within its two halves and the trip rod 11 thereof projecting through a hole in one of the halves and carrying a head or bottom 12. This bell I mount upon a swinging arm

13 by means of the bridge 14, said arm preferably tapering outward and extending beyond the bell as clearly shown in Fig. 2.

15 represents a plate similar to one leaf of a hinge and this plate is adapted to be secured to the inner face of a window frame by the screws 16 passing through suitable holes in said plate.

The arm 13 is pivoted to the plate 15 by the pintle 17 passing through the lugs 18 on the plate and the lug 19 on the arm so as to permit the arm to freely swing relative to the plate while giving it considerable strength to resist strains in a vertical direction for the purpose heretofore set forth.

20 represents a spring coiled around a portion of the pintle 17 the lower lug 18 being left shorter than the upper lug 18 to provide space for the accommodation of this spring. One end of this spring bears against the outer surface of the arm 13 as indicated at 21, while the opposite end thereof projects downward against the lower lug 18 as indicated at 22 and this arrangement will cause the spring to constantly exert the pressure upon the arm 75 tending to swing said arm inward.

From the foregoing description, the operation of my improvement will be obviously as follows, the plate 15 having been secured to the inner face of the window frame as shown and the lower sash having been closed, the arm will be swung by the spring into operative position bringing the button 12 of the trip rod immediately above the upper rail of the lower sash after which any attempt to raise the lower sash will force the trip rod 11 upward tripping the ringing mechanism of the bell, thereby continuing to sound an alarm until the ringing mechanism of the bell has been run down or the lower sash has been closed, thus providing effective protection against an unauthorized person gaining access through the window.

When the bell is in operative position, it not only provides for the setting off of the alarm on an attempt to be made to raise the lower sash, but it also locks the lower sash against being raised to any appreciable extent, since the bell and the arm carrying the same being in the path of travel of this sash

will prevent the raising of the latter, the arm and plate being of sufficient strength to resist any ordinary attempt to raise this sash.

When the bell is swung into operative position, the outer end of the arm 13 projects beneath the screw stud 23 set in the side rail of the upper sash, thus locking this upper sash against being opened.

To free the two sashes so that they may be opened is only necessary to swing the arm outward against the action of the spring until said arm and the bell carried thereby have passed out of the paths of said sashes and by slightly raising the lower sash the outer end of the arm will abut against the lower sash as indicated at 23^a, thereby holding the alarm out of active position so long as the sash is open, but upon the closing of the sash, the spring will immediately swing the arm into operative position thus eliminating the possibility of being left unprotected by a person forgetting to set the alarm. This is one of the essential features of my present invention since the usual burglar alarm requires manual setting or adjustment to put it in position for operation and by oversight it is often left unset and the window left unprotected, but when my device is used no care or thought on the part of the person closing the window is required, since as before stated the alarm automatically sets itself when the lower sash is closed.

Of course I do not wish to be limited to the exact details of construction herein shown and described as these may be varied within the limits of the appended claims without departing from the spirit of my invention.

Having thus fully described my invention, what I claim as new and useful is:—

40 1. In an alarm of the character described, a plate having holes therethrough for the passage of screws to secure said plate to a window frame, an arm pivoted to the plate by a pintle passing through lugs formed upon the plate and a lug formed upon the arm, a spring coiled upon a portion of the pintle between one of the lugs of the plate and the lug of the arm, one end of said spring bearing against the outer surface of the arm, the other end of said spring bearing against a lug of the plate, a trip bell secured to the arm in such a manner that when the arm is closed against the plate the trip of the bell will be positioned above the upper rail of the lower sash of the window and means secured to the upper sash in the path of the outer end of the arm when the latter is closed against the plate.

60 2. In a device of the character described, a plate having two lugs formed thereon, an arm having a lug formed on one end thereof, a pintle passing through the lugs to hinge the arm to the plate, a spring coiled around a portion of the pintle, said spring being adapted to swing the arm toward the plate,

a bridge secured upon the arm, and a trip bell mounted upon the bridge, the outer end of said arm extending beyond the bell.

In testimony whereof, I have hereunto affixed my signature.

OTWELL G. PETTYJOHN.
